CHARLES S. EVANS AND HERBERT PARKER, OF WALDEN, NEW YORK.

FOLDING RULE.

SPECIFICATION forming part of Letters Patent No. 778,019, dated December 20, 1904.

Application filed April 21, 1904. Serial No. 204,247.

To all whom it may concern:

Be it known that we, CHARLES S. EVANS and HERBERT PARKER, citizens of the United States, residing in Walden, Orange county, State of New York, have invented certain new and useful Improvements in Folding Rules, of which the following is a specification.

This invention relates principally to folding rules such as commonly used by carpenters and others, such rules being usually made of four sections hinged together; and its object is to provide the rule with suitable means whereby it may be used when required as a square for either inside or outside angles. To this end one of the rule-sections is provided with a blade which may stand at right angles to the rule-section and which may fold into parallelism therewith, so as not to be in the way when not required.

The invention consists in the provision of a simple, reliable, and inexpensive construction for this purpose.

A valuable feature of the invention resides in the provision of a positive stop which limits the opening movement of the blade, so that it cannot pass beyond the right-angle position, whereby liability of errors is avoided, and another feature of importance lies in the provision of means whereby the angularity of the blade to the rule-section may be finely adjusted, so that in the process of manufacturing they may be brought into exact right-angle relation and so that the parts may be subsequently trued up from time to time, if required. The parts are preferably so constructed that, if desired, the tool may be used as a square simply by opening the blade without unfolding the rule. The section of the rule that carries the foldable blade is of novel construction, consisting principally of a pair of plates or strips of metal, between which the blade folds and to which the blade is pivoted at the free end of the rule-section, a blade-controlling spring being also confined between said plates and extending along one edge thereof.

In the accompanying drawings, Figure 1 is a face view, and Fig. 2 an edge view, of a carpenter's rule made according to the present invention, the section provided with the

foldable blade being shown open. Fig. 3 is a view similar to Fig. 1, but showing the square-blade open. Figs. 4 and 5 show details of mounting of the square-blade, parts being broken away to exhibit the construction. Fig. 6 is a longitudinal section showing the construction of the adjustable stop that limits the opening movement of the square-blade. Fig. 7 illustrates the rule as entirely folded, but the square-blade as open, showing that the device may be used as a square without opening any rule-section.

In the several views like parts are identified by like signs.

While the invention is not limited to use upon a four-section rule, it is illustrated in connection therewith, sections 1 and 2 being connected by a hinge 3 and section 1 being connected by a main hinge 4 to the remaining two sections 5, the latter being connected by a hinge 6. Section 2, which, it will be observed, is an end section of the rule, consists principally of a pair of metal plates 7 8, riveted at their inner ends by rivets 9 upon an intervening leaf 10, the latter being one of the leaves of the hinge 3 and lying between the plates 7 8.

Between the plates at the free end of the rule-section is pivoted a blade 11, the pivot 12 being in the form of a rivet, which unites the ends of the plates. The blade 11 normally folds between the plates and parallel therewith and preferably flush with their outer edges, as at Fig. 4, and is of such length as to reach to the hinge-leaf 10, so that the rule-section has a nearly unbroken edge. Also mounted between the plates 7 8 is a spring 13 of the same thickness as the leaf 10 and extending along the rule-section from said leaf to the free end of the section, so that this side of the rule-section also presents an unbroken edge, the plates 7 8 being secured by rivets 14 to the base or inner portion of the spring and the latter being formed with a finger 15, which normally bears against the tip of a short arm 16, formed upon the pivoted end of the blade 11 to hold the latter in normal position, as at Fig. 4.

For convenience in opening the blade it is provided upon opposite sides with nicks 17, 100

while adjacent to said nicks the plates 7 8 are provided with cut-aways 18, Figs. 2, 3. When the blade is opened to right-angle position, as at Figs. 2, 5, and 7, its further movement is prevented by a stop 18, against which the short arm 16 of the foldable blade is pressed by the spring-finger 15, which at Figs. 4 and 5 bears upon opposite sides of said short arm. The positive stop for the blade is a feature of considerable value, since it conduces materially to the reliability of the implement when used as a square.

Preferably the stop 18 is so formed and mounted that it may be adjusted, and, as illustrated, it may consist of a cylindrical body confined between the plates 7 8, near the outer ends thereof, and having trunnions 19 20, having bearings in the plates 7 8, whereby the stop may be adjusted by a rotative movement, and the body 18 is formed eccentrically to said trunnions, so that by turning the same the angularity of the blade 11, which bears thereagainst, may be nicely adjusted, and hence said blade may be brought exactly into a right-angle relation with the rule-section 2. The trunnion 20 preferably projects through the plate 8 and its projecting end squared at 21, so that it may be turned by the use of a key or wrench, said projecting end occupying when the rule is folded a recess or niche 22, formed in the rule-section 1, opposite to which the rule-section 2 lies when the rule is folded. The stop, however, may be formed with other key-holds within the scope of the invention. Preferably the trunnion 19 is riveted to the plate 7, as at Fig. 6, so as to hold the stop firmly and prevent accidental disturbance thereof, the rivet not being so tight, however, as to prevent the stop from being turned when force is applied thereto for that purpose. It will be perceived that in manufacturing the foldable blade may, by means of the adjustable stop, be expeditiously brought to an exact right-angle relation to the rule-section and that the adjustment so effected will not be disturbed from ordinary causes in the use of the rule, while at any time by readjusting the stop the blade may be again trued up.

As will be observed at Fig. 7, the end section 2, which carries the foldable blade 11, lies edgewise against another of the rule-sections—viz., the section 5—while said blade opens from the outer side of said end section 2, so that the device may be used as a square without unfolding any section of the rule, which is oftentimes a great convenience. As will be also understood from Fig. 3, the device may be used as either an outside or an inside square—that is to say, either its outside edges or its inside edges may be brought into use, as may be required for use upon either outside or inside angles. The stop 18 of course determines mechanically the right-angle position of the blade upon the latter being opened.

Variations may be resorted to within the scope of the invention and portions of the improvements may be used without others.

Having thus described our invention, we claim—

1. A folding rule consisting of sections hinged together, one of said sections having pivoted to its free end a blade that may turn from a position parallel with said section to a position at right angles thereto, a spring being provided for holding said blade in either position, and a fixed stop being also provided against which said spring holds said blade when the latter is open; said stop being adjustable to bring the blade into exact right-angle relation with said section. 75

2. A rule having a folding blade and provided with an adjustable eccentric which serves to stop the blade when the latter is opened to a position at right angles with the rule, and a spring to hold said blade against the eccentric. 80

3. A rule-section comprising a pair of plates and an intermediate spring riveted together, a blade lying between said plates and pivoted thereto at the end of the rule-section and capable of turning to a position at right angles with the rule-section, and a stop against which said spring presses said blade when the latter is open; said stop being in the form of an eccentric mounted between said plates and having a key-hold, whereby it may be turned so as to bring said blade to exact right-angle relation with said rule-section. 90

4. A folding rule consisting of sections hinged together, one of said sections comprising a pair of plates connected together and an intermediate longitudinally-extending spring, and a blade confined between said plates and pivoted thereto at the end of the rule-section and capable of turning to a position at right angles to the rule-section, and also a stop against which said spring presses said blade when the latter is open; said stop being in the form of an eccentric mounted between said plates and having a projecting stem whereby it may be rotated, and the rule-section to which the blade-carrying section is hinged having a niche opposite to said projecting stem, for receiving the latter when the rule is folded. 105

5. A rule-section comprising a pair of plates and an intermediate spring, a blade lying between said plates and pivoted thereto and capable of turning to a position at right angles with the rule-section, and a stop against which said spring presses said blade when the latter is open; said stop comprising a body and trunnions, the body being confined between said plates and being eccentric to the trunnions, and the latter having bearings in the plates. 115 120

6. A rule-section comprising a pair of plates and an intermediate spring, a blade lying between said plates and pivoted thereto and capable of turning to a position at right angles with the rule-section, and a stop against which 130

said spring presses said blade when the latter is open; said stop comprising a body and trunnions, the body being confined between said plates and being eccentric to the trunnions; 5 one trunnion being riveted so as to hold the trunnion where adjusted, and the other trunnion being provided with a key-hold whereby the trunnion and stop may be rotated.

Signed at Walden, New York, this 15th day of April, 1904.
